(57) **CLAIM**

The ornamental design for a number plate, as shown and described.

DESCRIPTION

FIG. 1 is a perspective view of a number plate showing my new design.

FIG. 2 is a front view of the number plate.

FIG. 3 is a top view of the number plate.

FIG. 4 is a bottom view of the number plate.

FIG. 5 is a rear view of the number plate; and,

FIG. 6 is side view of the number plate, the opposite side being a mirror image thereof.

The numbers and letters printed or embossed on the number plate are provided for environmental purposes and do not form part of the claimed design.
